UNITED STATES PATENT OFFICE.

LYLBURN P. JAMERSON, OF ATLANTA, GEORGIA.

GUN.

1,320,233.

Specification of Letters Patent. Patented Oct. 28, 1919.

Application filed December 30, 1918. Serial No. 268,807.

To all whom it may concern:

Be it known that I, LYLBURN P. JAMERSON, a citizen of the United States, residing at Atlanta, in the county of Fulton and 5 State of Georgia, have invented new and useful Improvements in Guns, of which the following is a specification.

This invention relates to improvements in gun construction, and has particular application to guns of that type which employ 10 an explosive mixture to drive or propel the projectile.

In carrying out the present invention it is my purpose to provide a gun whereby 15 the projectile may be driven through the barrel of the gun by the exploding of a highly compressed explosive mixture behind the projectile, thereby enabling the shell or projectile to be thrown from the 20 gun without the use of powder that is now usually employed.

It is also my purpose to provide a gun of the type set forth which will embrace the desired features of simplicity and durability, 25 which may be constructed and operated at minimum expense, which will embody comparatively few parts and these so arranged and correlated as to reduce the possibility of derangement to a minimum and which 30 will be constructed in such manner that the explosive charge may be highly compressed in the explosion chamber so that when such charge is ignited the shell or projectile will be expelled from the gun by the maximum 35 energy developed by the ignited charge.

With the above recited objects in view and others of a similar nature, the invention resides in the construction, combination and arrangement of parts set forth in and 40 falling within the scope of the appended claims.

In the accompanying drawings:—

Figure 1 is a view in elevation of a gun constructed in accordance with my present 45 invention.

Fig. 2 is a longitudinal sectional view through the gun.

Fig. 3 is a cross sectional view on the line 3—3 of Fig. 2.

Fig. 4 is an enlarged detail view of one 50 of the projectiles removed from the barrel of the gun.

Fig. 5 is a fragmentary longitudinal sectional view through the gun showing a modified construction of the invention.

Referring now to the drawings in detail 1 designates a barrel and 2 an explosion chamber arranged at one end of the barrel 1 and in communication therewith and a greater diameter than the barrel 1, the transverse and longitudinal dimensions of the explosion chamber 2 being such that the proper volume of the explosive mixture may be delivered to such chamber. Arranged behind the explosion chamber 2 and, in the present instance, in axial alignment with the explosion chamber and the barrel 1, is a compression cylinder 3 having the head forming the rear wall of the explosion chamber. Mounted within the compression cylinder 3 and capable of reciprocatory motion therein is a piston 4 connected with one end of a pitman 5, the other end of which is journaled to a crank shaft 6. The crank shaft 6 may be driven from an internal combustion engine or electric motor or any other suitable form of prime mover so that rectilinear motion may be imparted to the piston 4 within the compression cylinder 3. In the present form of the invention, a supply pipe 7 is connected with the cylinder 3 adjacent to the head of such cylinder and located in the port that establishes communication between the supply pipe and the cylinder is an inwardly opening valve 8 that controls the flow of the explosive mixture into the cylinder. The head of the cylinder 3 is formed with a discharge port 9 that opens into the explosion chamber 2 and located in the discharge port 9 is an outwardly opening discharge valve 10 that controls the flow of the mixture to the explosion chamber. 11 designates a spark plug or other form of igniting device that is located in the explosion chamber and connected with a suitable source of electrical energy so that the mixture in the explosion chamber may be fired, the firing of the mixture being controlled by a timer that is driven from the crank shaft. 100

In Fig. 4 of the drawings I have shown one form of projectile and shell which may be used in connection with my improved gun and in this case the projectile embodies a body 12 which may be solid or of the explosive type, and a case 13 surrounding the body 12 at one end of the latter increasing in diameter from the body 12 toward the outer end of the shell, in the shape of a frustum of a cone. In the present instance 105 110

the explosion chamber is substantially frusto-conical in shape to receive the case 13, while the body 12 of the projectile extends into the barrel of the gun at the juncture of the 5 barrel with the explosion chamber.

In practice, the projectile is placed in the gun as just described and the prime mover of the crank shaft placed in operation. In the rotation of the crank shaft the piston in 10 the compression cylinder is operated and upon the outward stroke of said piston a charge of the explosive mixture is drawn into the compression cylinder through the inwardly opening intake valve 8. Upon the 15 compression stroke of the piston 4, the charge in the cylinder is driven through the exhaust valve 10 into the explosion chamber and compressed in such chamber so that when the spark plug is energized the compressed mixture may be fired to drive the 20 projectile body 12 out of the case and through the barrel of the gun toward its destination.

It will be noted that owing to the construction and arrangement of the valves 8 and 10, the exhaust valve remains closed upon the intake stroke of the piston 4, and the intake valve remains closed upon compression or exhaust stroke of the piston 4, 30 thereby assuring the proper delivery of the gas in the compression cylinder of the explosion chamber.

In the modified construction illustrated in Fig. 5 of the drawing I have shown the 35 compression cylinder as arranged at right angles to the barrel of the gun. In this case the end wall of the cylinder is connected with the source of gas supply while the side wall is connected with the explosion chamber. It will be understood, however, that the compression chamber may be arranged either coaxial with the gun barrel or at right angles thereto as desired.

Any desired form of the ejecting mechanism 45 may be employed to throw the empty cases or shells out of the explosion chamber while any approved type of magazine or

loading mechanism may be used to feed the projectiles into the explosion chamber.

I claim:

1. A gun comprising a barrel, an explosive chamber in axial alinement with said barrel, and including a portion equal in diameter to the diameter of the barrel to receive the projectile, the remaining portion of said chamber being of frusto-conical formation, a spark plug projecting into the said chamber, a cylinder having a restricted passage establishing communication between the cylinder and said chamber, a spring 60 pressed valve controlling said communication, a piston arranged to reciprocate within the cylinder, an explosive supply pipe communicating with said cylinder, whereby a charge is drawn into the latter upon the 65 intake stroke of the piston and delivered into the explosive chamber upon the compression stroke, and a valve arranged between the supply pipe and cylinder.

2. A gun comprising a barrel, an explosive chamber in axial alinement with the barrel, said chamber including a portion of equal diameter to the diameter of the barrel to receive the projectile, the remaining portion of the chamber being of frusto-conical 75 formation, a case of frusto-conical configuration fitted on one end of the projectile, and also arranged in that part of the explosive chamber of similar cross sectional configuration, a cylinder having a restricted 80 passage establishing communication between the latter and said case, a spring pressed valve controlling said communication, a piston arranged to reciprocate in the cylinder, an explosive supply pipe communicating with the cylinder, whereby a charge is drawn into the latter upon the 85 intake stroke of the piston, and delivered into the explosive chamber upon the compression stroke, and a valve arranged between the said supply pipe and cylinder.

In testimony whereof I affix my signature.

LYLBURN P. JAMERSON.
